BINDER FOR PHOTOGRAPHIC SLIDES OR SIMILAR ARTICLE

Clarence B. Mitchell, Chicago, Ill., and Herbert R. Leopold, Haverford, Pa., assignors to Optics Manufacturing Corporation, Philadelphia, Pa., a corporation of Illinois

Application September 30, 1957, Serial No. 47,917

Term of patent 14 years

(Cl. D61—1)

The single figure is a front perspective view of a binder for photographic slides or similar article, showing our new design, the rear being substantially a mirror image thereof. A portion of the drawing figure is diagonally lined to indicate transparency.

We claim:

The ornamental design for a binder for photographic slides or similar article, as shown and described.
